UNITED STATES PATENT OFFICE.

JAMES MONROE PALMER, OF CAMBRIDGE, MASSACHUSETTS.

VAPOR-STOVE.

SPECIFICATION forming part of Letters Patent No. 328,605, dated October 20, 1885.

Application filed April 14, 1884. Serial No. 127,760. (No model.)

To all whom it may concern:

Be it known that I, JAMES MONROE PALMER, of Cambridge, in the county of Middlesex, of the Commonwealth of Massachusetts, 5 have invented a new and useful Improvement in Apparatus for Vaporizing a Hydrocarbon and Mixing it with Air for the Purpose of Combustion; and I do hereby declare the same to be described in the following specification 10 and represented in the accompanying drawings, of which—

Figure 1 is a vertical section of a building with my improvement applied thereto. Fig. 15 2 is a vertical section of a burner of such apparatus.

The nature of my invention is defined in the claim hereinafter presented.

In Fig. 1 of such drawings, A represents the building having three stories, *a*, *b*, and *c*, 20 and a cellar, *d*. In the said cellar there is placed a closed reservoir or tank, B, for holding gasoline, such tank being provided with an air-forcing pump, C, which, as shown, is located in the first story and communicates 25 with the tank by a pipe, *d'*, such pipe being for forcing air into and condensing it within the tank and above its charge E of gasoline. From and opening out of the top of such tank there is extended a series of pipes, *g*, each of 30 them being led therefrom to the receiving-conduit *h* of a heating apparatus, D, E', or F, or that of a gas-lighting burner, G, located in some one or more of the stories of the building, there being to the pipe or to the conduit 35 *h*, so as to interrupt communication of the latter with such pipe, a stop-cock, *i*. The said receiving-conduit may be supposed to be provided with one or more suitable burners opening out of it, especially of the kind shown in 40 Fig. 2, and hereinafter described, which is what may be termed an "improved Bunsen burner," or one for intermixing air and the vapors of a hydrocarbon and burning the mixture for heating purposes.

45 Besides the series of pipes *g*, there is to the tank another series, *f*, each pipe of which extends down within the tank nearly to its bottom, and from the top of the tank is continued to and opens into the duct *h* in advance of the 50 stop-cock *i* of the pipe *g*, and there is in the duct *h*, and in advance of the entrance of the pipe *f* into it, another stop-cock, *k*.

The heating apparatus E' is shown as placed immediately under a boiler, I.

Each burner of each heating apparatus of 55 the two stories *a* and *b* may be supposed to be constructed as represented in section in Fig. 2, its stem *l* above the plug *m* of its stop-cock terminating in a jet, *n*, with a cup, *o*, encompassing such jet, and opening into a mouth-piece, *p*, for discharge of the mixture of air and gasoline-vapor in numerous jets. There are holes *q* in the sides of the cup *o*, such holes being for supplying air to the cup. On letting into the cup a little of the gasoline and 60 setting it on fire the burner may be heated, so as to cause to be vaporized the gasoline that may be discharged from the jet *n*.

Within the stem *l* of the burner is a packing, *s*, of asbestos or some other suitable absorbent material, through which the gasoline passes to the stop-cock, and thence to the jet *n*. Furthermore, surrounding the stem *l* is a cup, *t*, from which a pipe, *u*, is led into the cellar, and there provided with an S-trap, *v*, and 75 enters a waste-receiving cistern or vessel, *w*.

In the operation of the apparatus the gasoline or hydrocarbon within the cistern or tank B will, on the cock *k* of any of the pipes *h* being opened, be driven by the condensed air 80 into the burner or burners of such pipe, and may be vaporized and burned by such burner or burners. By closing the cock *k* of such pipe and opening the cock *i* of the return-pipe *g* the gasoline elevated in the pipe *f* will 85 at once descend or fall back from the pipe *f* into the tank B. Now, as the pipe *f* above the gasoline-tank will be charged with air after the gasoline may have run down within such pipe, such air, on the stop-cock of the 90 burner being opened and the stop-cock of the air-pipe *g* being closed, will be driven up into and through the burner. In its passage through the packing *s* such air will be carbureted by the gasoline retained in such packing, and 95 therefore will from the jet *n* issue charged with the vapors of the hydrocarbon, and at once may be inflamed. Thus by means of the packing the said air will be put in a condition to be burned before it can escape into the 100 apartment and infuse therein any noxious or dangerous vapor or disagreeable effluvium.

Any hydrocarbon liquid that may escape from the cup *o* or upper part of the burner

and flow down upon the outer surface of the stem *l* will be intercepted by the cup *t*, and by the pipe *u* will be conveyed to and through the **S**-trap and into the waste-receiver *w*.

5 From the above it will be seen that I have attached to such burner or series of burners means for causing its gasoline-supplying pipe to be subsequently emptied of the hydrocarbon within it after the cock of such pipe may have 10 been closed, such means being the pipe *g*, having the stop-cock *i*, and extended to and opening out of the upper part of the closed tank *B*, the object of so emptying the pipe being to increase the safety of the apparatus by preventing leakage of the hydrocarbon vapor from such pipe or from the burner. It will further be seen that there are means of carbureting the air that will be driven from the pipe *f* by the return or upward flow of the 15 hydrocarbon within it, such means of carbureting the air being the packing *s* more or less charged with the hydrocarbon.

I am aware of the United States patents to J. S. Hull, Nos. 283,246 and 241,219, and I 20 disclaim anything therein. In the latter patent is described a device for effecting a preliminary heating of the burner before the oil

flows to it. In such patent are shown tanks for the oil, for compressed air, and for gasoline. Pipes connect these several tanks, there being 30 one each side of a connecting-pipe, where it joins another, a cock like in my device. Compressed air passes from the air-tank to the gasoline-tank, is carbureted, and the gas passes to the burner and is illuminated, heating the 35 burner when the oil is turned on. My device differs from the above, and the difference is set forth in the claim.

I therefore claim—

The tank *B* and its air-compressing apparatus, in combination with the gasoline-supply pipe *f*, leading from the bottom of the tank, the return-pipe *g*, leading from the top of the tank, a burner for the gasoline, and the pipe *h*, having the cocks *i* and *k*, the pipe *f* 40 leading into pipe *h* between the said cocks, and the pipe *g* into pipe *h* beyond both cocks on the side away from the burner, as and for the purpose set forth.

JAMES MONROE PALMER.
